(57) **CLAIM**

The ornamental design for an infrared receiver, as shown and described.

DESCRIPTION

FIG. 1 is a plan view of an infrared receiver according to the invention;

FIG. 2 is a right side view of the infrared receiver of FIG. 1;

FIG. 3 is a left side view of the infrared receiver of FIG. 1;

FIG. 4 is a bottom view of the infrared receiver of FIG. 1;

FIG. 5 is a top view of the infrared receiver of FIG. 1;

FIG. 6 is a plan view of the infrared receiver of FIG. 1 with a surrounding cover plate; and,

FIG. 7 is an isometric view of the infrared receiver with surrounding cover plate of FIG. 6.

The broken line showing on FIGS. 1-7 is for illustrative purposes only and forms no part of the claimed design.
